SOLE EDGE INKING MACHINE

Paul H. Dixon, Wenham, Mass., assignor to
 United Shoe Machinery Corporation, Borough
 of Flemington, N. J., a corporation of New
 Jersey

Application March 8, 1940, Serial No. 322,996

27 Claims. (Cl. 12—31)

The present invention pertains to a machine for applying a coating to a shoe part and as embodied herein is adapted to apply a uniform coating of ink to the peripheral edge of a sole attached to a shoe.

The application of ink to the peripheral edge of shoe soles by means of a toothbrush or small piece of sponge is still employed to a great extent due to the fact that as yet no simple applying means has been developed that will impart a uniform coating of ink to the edge of the sole, with one passage of the work, fast enough to compete with the hand methods.

The object of the present invention is, therefore, to provide a machine embodying means capable of rapidly applying a uniform coating of ink to the edge of an attached shoe sole without soiling the upper.

The peripheral edge of a sole generally is not a plane surface but is provided with some predetermined edge design and, therefore, frequently its surface includes one or more ribs or grooves extending lengthwise of the sole edge. It is evident, therefore, that the inking can be satisfactorily accomplished by making a series of closely spaced marks on the edge of the sole, such as might be made by a drawing pen. That is, if the ink is applied by a plurality of fine marking surfaces or points, the ink will be applied not only to the ribs but also to the grooves which would be passed over by a broad surface or point. This is attained as a feature of the present invention by a plurality of closely spaced blades, the lower edges of which normally lie in a common plane, and to which ink is supplied in the spaces between the blades, the blades being independently movable with respect to each other and freely displaceable from said common plane by the irregularities of the edge of the sole presented thereto.

The thickness of a shoe sole varies considerably with the type of shoe and, therefore, another feature of the invention resides in means for retracting certain of the blades and holding them in a displaced position so that the blades not in contact with the edge will not overlap the surface of the sole.

While the quantity of ink carried by the blades is controlled to a large degree by a valve, which is opened only during the application of the sole to the blades, there is a tendency for sufficient ink to accumulate in the retracted blades, since that ink is not being used, to overcome the capillary attraction between the blades and permit a discharge of the ink even if the drawing out

action of the work is not present. Another feature of the invention is found in means for withdrawing the excess ink from the retracted blades and returning the ink to the ink reservoir.

The specific embodiment of the invention will now be described with reference to the accompanying drawings, in which

Fig. 1 is a side elevation, partly in section, showing the machine;

Fig. 2 is an enlarged perspective view, partly in section, of the horn on which the ink-applying device is supported;

Fig. 3 is a section on the line III—III of Fig. 1;

Fig. 4 is an enlarged vertical section longitudinally of the ink-applying device;

Fig. 5 is an enlarged section taken on line V—V of Fig. 6;

Fig. 6 is an enlarged section of the applying blades showing their disposition when a beaded sole is pressed against them; and

Fig. 7 is an enlarged section of the applying blades showing welt-bead guards.

Referring to Fig. 1, the machine is shown as comprising generally a base 10 and one or more ink receptacles 12 mounted on the base, each receptacle being provided with a horn 14 carrying an ink-applying device.

The base 10 comprises a hollow pedestal-like casting having a flat top bored at 16 to receive a column 18, the lower portion of which extends into the base through the bore 16 and thence into a hollow post 20 extending upwardly from the bottom of the base, the upper end of the post being split and clamped about the column by bolts 22. In order to provide a more extensive bearing surface at the bore 16, a collar 24 is screwed to the under side of the pedestal so that it is concentric with the bore 16.

The column 18 extends vertically upward from the top of the pedestal and is reduced somewhat in diameter so as to provide a bearing shoulder 26 for the lower end of a hub 28 which is rotatably supported by the column.

The hub terminates short of the top of the column and on the top there is fixed a cap 30 adapted to support an electric motor 36 arranged to drive a shaft 38 associated therewith. The cap also supports a control switch 40 for the motor and a conventional lamp and shade 34 above the inking horn 14.

In practice, the most common edge stains are black or brown, and in order to permit ready change from one color to another, this machine is provided with two ink receptacles, either one

of which may be quickly moved into position for immediate use. The ink receptacles 12 are identical in construction and are supported on a platform 13 extending radially from the hub at its lower end. In order to hold the receptacles in place thumb-screws 21 are provided which are threaded through lugs 23 extending radially from the hub, the lower end of the screws bearing against horizontal surfaces 19 provided on the receptacles whereby the receptacles are forced against the platform 13. Each receptacle has a bottom 44 below which there is housed a gear pump 46 which is driven by a shaft 48 which extends upwardly through the top of the receptacle, the pump being provided for pumping ink in the receptacle to the horn 14 through passages which will be described hereinafter. By turning the hub 28 on the column, and consequently the receptacles, either of the shafts 48 may be connected to the driven shaft 38 by a coupling 50.

The coupling consists of a collar 41 fixed to the shaft 38 by means of a set screw, the lower side of the collar being provided with teeth 43 arranged to occupy the open end of a diametrical slot 45 formed in the upper end of a sleeve 47 which is mounted for longitudinal movement on the shaft 48 and is held in engagement with the teeth 43 by a spring 49 backed up by a collar 51 fixed to the shaft 48. A pin 53 mounted on the shaft 48 occupies the lower end of the slot 45, thereby preventing rotation of the sleeve 47 on the shaft so that the slot 45 and teeth 43 will always be in alignment. By pressing the sleeve 47 down, the teeth 43 may be released from the slot 45 to disconnect one of the shafts 48 whereupon the hub 28 may be turned on the column so as to bring the other shaft 48 into alignment with the shaft 38. When either one of the shafts 48 is in alignment with the shaft 38, the hub is locked in position by a latch 52 which is pivoted at 54 between a pair of ears 51 formed on the base 10. The upper end of the latch is arranged to drop into one of two diametrically disposed slots 56 formed in the edge of the platform 13, the latch being held in the slot by a spring 58. The top of each receptacle is provided with a cover 60.

The outer wall of each receptacle is provided with a circular opening 66, and a flat casting 62, the upper end of which is bored at 64, is bolted to the wall with the bore 64 in alignment with the opening 66 formed in the wall. The aligned opening 66 and bore 64 in effect form a socket adapted to receive the butt end of the horn 14. The casting is provided with supply and return passages 65 and 67, the passage 65 terminating at its upper end in the side of the bore 64, and the passage 67 terminating in the bottom of the bore 64. The lower end of the passages 65 and 67 are connected with passages 65' and 67', formed in the receptacle which in turn are connected to the discharge and intake sides of the pump casing, respectively.

The horn 14 is cylindrical and two passages 68 and 70, separated by a partition 69 (Fig. 4), are formed lengthwise thereof, the lower passage 68 being connected to the return passage 67 by an aperture 68' formed in the bottom wall of the passage 68, and the upper passage 70 being connected to the supply passage 65 by an aperture 70' formed in the side wall of the passage 70. The upper wall of the horn (Fig. 2) is cut away from a point approximately half way between its ends to its outer end so as to expose the 75

cylindrical passage 70. The exposed part of the passage is squared out, as shown at 72 in Fig. 5. Near the end of the horn the passage 68 is enlarged somewhat to form a basin 71, and the partition 69 which separates the passages 68 and 70 is cut away so that they are connected, leaving ledges 73, as illustrated in Figs. 2 and 5. A relatively narrow slot 74 is formed in the bottom wall of the basin, said opening extending to the outer end of the horn. An arm 76 of rectangular cross-section is disposed axially in the passage 70, the outer end of the arm being enlarged and provided with a socket portion 78 having a socket 77. The lower portions of the rear wall 80 and the side walls 81 of the socket are adapted to rest upon the edge of the partition 69 and the ledges 73. The socket portion 78 is of approximately the same dimension as the squared-out section 72 (Fig. 5) of the passage 70 and is guided for vertical movement with respect thereto. A portion of the lower edges of the side walls 81 are beveled at 79 so as to provide ink pockets 83 along each side of the member 78 which are cut off at their inner ends from the passage 70 by the rear wall 80. Normally the socket portion 78 is held in its lowermost position, as will hereinafter be described, so that the rear wall 80 and side walls 81 thereof act as a valve or partition which cuts off communication between the passage 70 and the basin 71.

The inner parallel walls 82 of the side walls 81 of the socket 77 are provided with a plurality of closely spaced grooves 84 for the reception of a plurality of thin blades 86 in the spaces between which the ink flows down for application to the work. The blades are free to slide vertically in the grooves and are retained therein by T-shaped heads 88 which rest on the top of the socket 77. The lower ends of the blades extend into the basin 71 (Figs. 2 and 5) where they are reduced in breadth at 90. The reduced extensions project from the slot 74 in the bottom wall of the basin and the ends thereof are slightly convex. As illustrated in Fig. 4, the blades are sloped downwardly to the front, and while this is not essential to the operation of the machine, it makes it easier for the operator to hold the work against the blades. The outer end of the horn is covered by a combined guard and gage 92, which will be described hereinafter, thereby providing an end wall for the basin 71, the gage 92 being secured to the end of the socket portion 78 by means of screws 94.

The blades 86 are yieldably held with their ends in a common plane by a resilient strip 95 having a narrow ridge 96 thereon adapted to bear against the upper edges of the blades. The strip is held in place above the blades by a cap 98 which is provided with a recess 100 in its underside to receive the strip. One wall of the cap extends rearwardly thereof and provides an anchor plate 102 (Fig. 4) by which the cap may be secured to the arm 76. A pair of screws 104 are provided for securing the anchor plate to the arm.

Frequently it is not necessary or desirable to use all of the blades, for example, when the edge of the sole is not thick enough to extend across the ends of all of the blades, and, therefore, means are provided for rendering part of the blades inoperative. To this end one side of the cap is cut away to expose the T-shaped heads of the blades. In the space provided by the cut-away wall there is arranged a narrow bar 106,

the outer end of which is offset and turned up at 108 to afford a finger hold (Fig. 4). The inner end of the bar 106 slides in a slot 110 cut on the under side of the anchor plate 102. When it is desirable to retract a portion of the blades, they are pushed up by pressing on their lower ends until the T-shaped heads are raised far enough above the top surface of the socket 78 to permit the bar 106 to be pulled forward beneath the heads so as to hold the blades in raised position.

Since the admission of the ink from the passage 70 to the basin 71 is controlled by the gate valve 80—81, the arm 76 is arranged so that it may be raised and lowered. To this end, a headed screw 112 is threaded into a bore 113 formed in the inner end of the arm 76, and a thumb-piece 114 is mounted thereon, the thumb-piece having a substantially semicircular flange 116 on its under side which conforms to the bottom half of the passage 70 and rests behind a semicircular abutment 118 which projects upwardly from the bottom of the passage 70, the flange 116 acting as a fulcrum on which the arm may be tilted and also serving to retain the arm within the horn.

The thumb-piece 114 is recessed at 120 so as slidably to receive the head of the screw 112, and a spring 121 is mounted between the bottom of the recess 120 and the under side of the head of the screw. A sleeve 122 is threaded into an enlarged portion of the bore 113, the sleeve being disposed axially on the screw 112 behind the thumb-piece 114. This sleeve is provided with a head 124 by which it may be turned whereby the axial position of the thumb-piece may be changed to vary the resistance of the spring 121. To compensate for the axial movement of the thumb-piece along the screw 112, the screw 112 must be adjusted axially in the arm. By simply pulling back on the thumb-piece 114 and lifting it above the abutment 118, the arm, including the head, may readily be dismounted from the horn.

The flange 116 acts not only as a fulcrum but forms an adjustable end wall for the passage 70 whereby the level of the ink in said passage may be governed, that is, the flange is semicircular and occupies the lower half of the passage 70. When the upper edge of the flange is horizontal, the ink will rise to the depth of the radius of the flange. By twisting the thumb-piece 114, however, the flange may be tilted so that its edge lies at an angle with the horizontal. This, of course, lowers the wall at one side, thereby permitting part of the ink to run back into the reservoir. The provision of this overflow wall maintains the level of the ink in the passage substantially constant, at a selected depth, at all times.

In order to insure positive closing of the gate valve 80—81 when the pressure of the shoe against the edges of the blades is withdrawn, the arm 76 is held down by a spring-pressed plunger 125 slidably mounted in a sleeve 126 screwed through a bracket 128 which is fixed to the top side of the horn 14 by a thumb-screw 130. A screw 132 is threaded into the upper end of the sleeve and bears against one end of a spring 133 the other end of which bears against the plunger 125. By turning the screw 132, the pressure on the plunger may be varied, thereby permitting adjustment of the pressure exerted on the arm 76 by the plunger. The amount of ink absorbed by the edges of soles varies considerably with the character and quality of the leather and,

therefore, the lower end of the sleeve 126 is arranged to limit the upward movement of the arm 76, thereby governing the amount the gate valve 80—81 may be opened.

When the edge of the sole S is presented to the blades, it is desirable to have some means for guiding the work as it is turned against the blades and also some means for preventing the ink from getting onto the upper. To this end, the edge gage 92 is arranged so that its lower edge projects below the plane of the edges of the blades and will ride in the crease between the sole S and the upper U, as illustrated in Fig. 6. In this way the member 92 acts as a guide to insure accurate registration of the edge of the sole with the blades and at the same time prevents the ink from getting on the upper. The inner surface of the member 92, however, is furnished with sufficient ink from the space between it and the adjacent blade to insure inking the upper surface of the sole adjacent to the upper. In certain kinds of shoes a bead welt or storm welt W is employed, as shown in Fig. 7. When a single guide 92 is employed, there is some tendency for the guide to slip off the bead into the outer groove between the welt bead and the upper. This, of course, permits the ink to run down onto the bead and soil it. To prevent this, a second guide 134 is provided (Fig. 7). The guide 134 is supported on the shank of a screw 136 which projects from the guide 92 and is provided with a fulcrum 138 about which it may be tilted. A screw 140 is threaded through the upper end of the gage and is arranged to bear against the gage 92 so that adjustment of the screw 140 will change the angular position of the gage 134 about its fulcrum point. By this arrangement the lower edge of the gage 134 may be adjusted to and from the gage 92 in accordance with the dimensions of the welt W.

The ink is pumped through the passage 65 by means of the gear pump 46 and fills the passage 70 to a depth determined by the position of the flange 116. When the edge of the sole is pressed against the bottom edges of the blades 86, the arm 76 having the socket portion 78 is lifted first against the spring-pressed plunger 125 so as to open the gate valve 80—81. This permits the ink to fill the pockets 83 and to flow into the basin 71 from these pockets along each side of the blades, and consequently, to fill the spaces between the blades. The gear pump inlet is connected to the return passage 67 so that when the pump is running, a slight suction is provided in this passage and also the passage 68, the inner end of which is closed by the abutment 118. The suction maintained is sufficient to draw the excess ink in the basin into the return passage. At certain times, as heretofore indicated, some of the blades are withdrawn from active use and there is a tendency for the ink in such blades to accumulate since it is not used up. In the present case, however, the aforementioned suction is sufficient to draw any excess of ink which accumulates on the unused blades into the return passage. It is to be observed in Fig. 4 that the passage 68 slopes toward the receptacle 12 so that, even though no suction were maintained in the passage, the excess ink would tend to run back to the receptacle by gravity. The suction, while not indispensable, does facilitate the return of the ink, particularly when it is sluggish because of its high viscosity or because of the presence of considerable coloring matter.

After the valve 80—81 is open, further pressure

of the shoe sole against the blades will cause them to yield somewhat, that is, the upper ends will be pressed into the rubber strip 95, some of the blades yielding more than others according to the profile of the edge of the sole (Fig. 6). When the edge of the sole S to which the ink is to be applied is not thick enough to extend across all of the blades, as previously indicated, some of the blades may be retracted, as shown in Fig. 7, by drawing the bar 106 beneath the shoulders 88 of the blades.

When the preliminary adjustments have been made, the operator holds a shoe with the edge of its sole against the blades, obtaining the proper registration by positioning the gage 92 in the crease between the upper and sole, and then lifts the shoe up so as to open the valve 80—81. Holding the shoe firmly in this position, he then proceeds to move it lengthwise so as to make a complete turn, thereby applying a uniform coating of ink to the edge of the sole.

Having described my invention, what I claim as new and desire to secure by Letters Patent of the United States is:

1. In a machine for inking the edge of an outsole, a plurality of closely spaced blades, said blades having lower edges which normally lie in a common plane, and means for supplying ink to the spaces between the blades, each blade being independently mounted and freely displaceable from said common plane by the irregularities of the edge of the sole presented thereto.

2. In a machine for inking the edge of an outsole, a plurality of parallel blades arranged to provide a plurality of capillary spaces between adjacent blades, said blades having lower edges which lie in a common plane, and means for supplying ink to the capillary spaces between the blades, each blade being independently mounted and free to be displaced from said common plane by any irregularity in the edge of a sole presented thereto.

3. In a machine for applying ink to the edge of a sole, a plurality of closely spaced blades, and means for supplying ink to the spaces between said blades, each of said blades having a marking surface comparable in thickness to a pen point, said blades being yieldable independently to accommodate themselves to the irregularities of the edge of the sole.

4. In a machine for applying ink to the edge of a sole, a plurality of spaced blades, and means for supplying ink to the spaces between said blades, each of said blades having a marking surface comparable in thickness to a pen point and being yieldable independently to accommodate itself to the irregularities of the edge of the sole, said spaces between the blades being commensurate with the thickness of the blades.

5. In a machine for applying ink to the edge of a sole which includes one or more ridges or grooves, a plurality of spaced parallel blades and means for supplying ink to the spaces between said blades, each of said blades having marking surfaces substantially less in thickness than the width of a ridge or groove, said blades being yieldable independently of each other so as to conform to the edge of the sole.

6. In a machine for inking the peripheral edge of an outsole, a plurality of means for applying ink to the edge of the sole, means including a passage for supplying ink to said applying means, and means for supporting the applying means, a portion of said supporting means being con-

structed and arranged to close the passage to separate the ink supplying means from the applying means, said supporting means being movable by the application of pressure to any one of said applying means to open said passage to permit the ink to flow from the supplying means to said applying means.

7. In a machine for inking the edge of an attached or unattached outsole, a plurality of means for applying ink to said edge, a passage for supplying ink to said applying means, means operable by the movement imparted to said applying means when the work is presented thereto to open said passage from said supplying means to said applying means, and means to render one or more of the applying means inoperative.

8. In a machine for inking the edge of an attached or unattached outsole, a plurality of parallel blades having edges lying in a common plane, means for supplying ink to said blades, means operable upon presentation of the work against the edges of the blades to connect said ink supply with the parallel blades, and a member co-operable with said blades to hold one or more of the same inoperative with respect to the remaining blades.

9. In a machine for inking the edge of an attached or unattached outsole, a plurality of parallel blades, each blade having a shoulder at one end and an edge at the other end, said edges lying in a common plane, means for supplying ink to said blades, means operable upon presentation of the work against the edges of the blades to connect said ink supply with the parallel blades, and a member movable into engagement with said shoulders to hold one or more of said blades in a retracted position.

10. In a machine for inking the edge and adjacent margin of the sole of a shoe having a storm welt, means for applying ink to the edge of the sole, means for supplying ink to said applying means and means to prevent the application of ink to the welt comprising a gage arranged to extend into the crease between the sole and welt, another gage arranged to occupy the crease between the welt and upper, means on said second-named gage for tiltably supporting said second-named gage on the first-named gage, and means for tilting said second-named gage about said supporting means whereby the second-named gage may be spaced from the first-named gage to accommodate any thickness of storm welt.

11. In a machine for inking the edge of an outsole, a plurality of spaced blades for applying ink to the edge of the sole, means for supplying ink to the spaces between said blades, said blades having lower ends arranged to lie in a common plane and being yieldably held in said common plane by a resilient member engaging their upper ends.

12. In a machine for inking the edge of an outsole, means for applying ink to the edge of the sole, a source of ink, a valve between said ink applying means and said source, said valve being movable upon the presentation of the edge of the sole to the applying means to open the valve, means for resisting the opening of the valve, means for varying the resistance of said resisting means, and means limiting the opening of the valve beyond a predetermined amount, said limiting means being adjustable to vary the limit to which the valve may be opened.

13. In a machine for inking the edge of an outsole, a plurality of blades for applying ink to

the edge of the sole, a basin having an opening in its bottom, an arm fulcrumed at one end and supporting the blades at its other end with their lower ends extending into said basin and through the opening therein, a passage for supplying ink to the basin, and a valve between the supply passage and the basin, said valve forming a part of the arm, the application of pressure to the lower ends of the blades operating to open the valve to permit ink to flow from the supply passage to the basin.

14. In a machine for inking the edge of an outsole, a plurality of blades for applying ink to the edge of the sole, a primary reservoir, a passage for carrying ink from the primary reservoir to the blades, a valve in said passage, the application of pressure to the blades operating to open said valve, and a return passage for returning excess ink from the blades back to the primary reservoir.

15. In a machine for inking the edge of an outsole, a plurality of blades for applying ink to the edge of the sole, a primary reservoir, a passage extending from said reservoir to a point adjacent to the blades for delivering ink to said blades, a passage extending from a point adjacent to the blades to the reservoir for returning excess ink from the blades to the reservoir, and means for pumping the ink through said delivery passage and for maintaining a vacuum in the return passage.

16. In a machine for inking the edge of an outsole, a plurality of inking devices, each inking device being adapted to apply ink to the edge of the sole, a reservoir for each inking device, passages for conducting the ink from the reservoirs to the inking devices, a pump associated with each reservoir for pumping the ink, and common means for operating either of the pumps, said reservoirs being so constructed and arranged that only one of the reservoirs and its pump may be positioned to be connected to said common operating means at a given time.

17. In a machine for inking the edge of an outsole, a column, a plurality of reservoirs rotatably supported on said column, an ink-applying device carried by each reservoir, a pump associated with each reservoir for supplying ink to the applying device mounted thereon, common means for operating the pumps, said reservoirs being constructed and arranged so that they may be turned on said column to bring any one of them to a position to be connected to said common operating means, means for locking the selected reservoir in position, and means for connecting the common operating means to the pump.

18. In a machine for inking the edge of an outsole, an ink reservoir, a horn fixed thereto, an ink-applying device, means for supporting the ink-applying device at the free end of said horn, a passage in said horn for conducting ink from the reservoir to the ink-applying device, and means associated with said first-named means to cut off said passage from said ink-applying device.

19. In a machine for inking the edge of an outsole, an ink reservoir, a horn fixed thereto, an ink-applying device supported at the end of the horn, passages in said horn for supplying ink from the reservoir to the ink-applying device and for returning the excess ink from the ink-applying device back to the reservoir, and a valve for controlling the flow of ink through the supply passage.

20. In a machine for inking the edge of an outsole, an ink reservoir, a horn fixed thereto, an ink-applying device supported at the end of the horn, a passage in said horn for supplying ink from the reservoir to the ink-applying device, a valve for controlling the flow of ink through said passage, a second passage in said horn for returning excess ink from the ink-applying device to the reservoir, and means for maintaining a vacuum in said return passage.

21. In a machine for inking the edge of an outsole, an ink reservoir, a horn having a passage therein fixed to said reservoir, an ink-applying device, an arm mounted in said passage for supporting the ink-applying device at the free end of the horn, and means for retaining the arm in the passage, said means constituting a closure for the inner end of the passage and being adjustable to govern the depth of the ink in the passage.

22. In a machine for inking the edge of an outsole, an ink reservoir, a horn having a passage therein fixed to said reservoir, an ink-applying device, an arm mounted in said passage for supporting the ink-applying device at the free end of the horn, a portion of said arm constituting a valve in said passage, and means for retaining the arm in the passage, said means constituting a fulcrum at the inner end of the arm about which the arm may be tilted to open the valve.

23. In a machine for inking the edge of an outsole, an ink reservoir, a horn having a passage therein fixed to the reservoir, an ink-applying device, an arm mounted in said passage for supporting the ink-applying device at the free end of the horn, a thumb-piece rotatably secured to the end of the arm, a flange formed on said thumb-piece shaped to conform to the bottom half of the passage, and an abutment projecting upwardly from the bottom of the passage behind which the flange is seated for retaining the arm in the passage.

24. In a machine for inking the edge of an outsole, an ink reservoir, a horn having a passage therein fixed to said reservoir, an ink-applying device, an arm mounted in said passage for supporting the ink-applying device at the free end of the horn, a portion of said arm constituting a valve in the passage, a thumb-piece rotatably and yieldably secured to the end of the arm, a flange formed on said thumb-piece shaped to conform to the bottom half of the passage, and an abutment projecting upwardly from the bottom of the passage behind which the flange is seated for retaining the arm in the passage, said flange providing a fulcrum about which the arm may be tilted to open the valve.

25. In a machine for inking the edge of an outsole, an ink reservoir, a horn having a passage therein fixed to said reservoir, an ink-applying device, an arm mounted in said passage for supporting the ink-applying device at the free end of the horn, a thumb-piece rotatably secured to the end of the arm, a substantially semicircular flange formed on said thumb-piece adapted to fit the bottom half of the passage and to close the same, and an abutment projecting upwardly from the bottom of the passage behind which the flange is seated for retaining the arm in the passage, the diametrical edge of the flange being tiltable by rotation of the thumb-piece to lower one side thereof.

26. In a machine for inking the edge of an outsole, an ink reservoir, a horn fixed to said reservoir, a plurality of ink-applying blades, an

arm associated with said horn having a socket member at its end for supporting said blades at the end of the horn, a basin at the end of the horn having an opening in its bottom through which the lower ends of the blades project, a passage in the horn, pockets extending along opposite sides of the basin closed at their inner ends from the passage and arranged to receive ink from said passage, the lower edge of the socket member forming a closure between the passage and the basin which may be opened by the application of pressure to the ends of the blades.

27. In a machine for inking the edge of an outsole, an ink reservoir, a horn fixed to said reservoir, a plurality of ink-applying blades, an arm associated with said horn having a socket at its end, grooves in said socket for slidably receiving said blades for independent relative movement, said blades having shoulders at their upper ends arranged to rest against the top of the socket and lower ends arranged to project below the bottom of the socket, and a passage in said horn for supplying ink to said blades intermediate their ends.

PAUL H. DIXON.
